UNITED STATES PATENT OFFICE.

WILLIAM H. SAART, OF ATTLEBORO, MASSACHUSETTS, ASSIGNOR TO THE W. H. SAART COMPANY, A CORPORATION OF MASSACHUSETTS.

DESIGN FOR A PICTURE-FRAME.

42,951.

Specification for Design.

Patented Aug. 27, 1912.

Application filed June 10, 1912. Serial No. 702,896. Term of patent 3½ years.

To all whom it may concern:

Be it known that I, WILLIAM H. SAART, a citizen of the United States, residing at Attleboro, in the county of Bristol and State of Massachusetts, have invented a new, original, and ornamental Design for Picture-Frames, of which the following is a specification.

In the accompanying drawing which forms a part of this specification,—the

I claim:

The ornamental design for a picture frame, as shown.

WILLIAM H. SAART.

Witnesses:

HORATIO E. BELLOW,
RALPH C. ESTES.
